DRAIN TILE BAND

Filed Sept. 1, 1927

UNITED STATES PATENT OFFICE

GLENN F. BUTLER AND CHARLES L. HAMAN, OF DETROIT, MICHIGAN

DRAIN-TILE BAND

Application filed September 1, 1927. Serial No. 216,880.

This invention relates to means for holding adjacent ends of drain tiles in alignment, the principal object being to provide a device that will be simple in construction, easily applied, efficient in use and economical to manufacture.

Another object is to provide a device for holding the ends of drain tiles in alignment, preventing dirt from entering the joint between the tiles, and in which means are provided for the flow of water between the band and the tiles to the joint between the tiles.

A further object is to provide a device for holding the adjacent ends of drain tiles in alignment comprising a band of flexible material adapted to overlap the joint between the tiles and provided with means on at least the surface thereof which contacts against the surfaces of the tiles for permitting the flow of water between the band and the tiles while holding the ends of such tiles in substantial alignment.

The above being among the objects of the present invention, the same consists in certain features of construction and combinations of parts to be hereinafter described with reference to the accompanying drawings, and then claimed, having the above and other objects in view.

In the accompanying drawing which illustrates suitable embodiments of the present invention, and in which like numerals refer to like parts throughout the several views,—

Fig. 1 is a side elevation of the end portions of a pair of substantially abutting drain tiles, such ends being held in alignment by a device of the present invention.

Fig. 2 is a sectional view taken on the line 2—2 of Fig. 1.

Fig. 3 is an enlarged fragmentary sectional view of the band only, taken on line 3—3 of Fig. 1.

Fig. 4 is an enlarged sectional view taken on line 4—4 of Fig. 1.

Fig. 5 is a view similar to Fig. 4 illustrating a modified manner of securing the ends of the band together in position over the ends of the tiles.

Fig. 6 is an enlarged fragmentary sectional view of a modified form of band.

Fig. 7 is an enlarged sectional view taken as on the line 4—4 of Fig. 1 illustrating the manner in which the modified band shown in Fig. 6 is secured in place over the ends of the drain tiles.

55

Fig. 8 is a view taken as on line 4—4 of Fig. 1 illustrating a modified manner of securing the band shown in Fig. 3 over the adjacent ends of the tiles.

60

In the use of drain tiles it is a frequent occurrence to find that the adjacent ends of the tiles are out of alignment, thus having permitted earth to enter the interior of the tiles and plug the same. When such condition has occurred, it is invariably necessary to dig up the tiles, clean them out and replace them, which operation entails considerable time, labor and expense. Such misalignment invariably occurs when tiles are first laid or shortly thereafter on account of the earth not being properly tamped whereby upon back-filling or consequent settling of the earth the tiles move and get out of their respective aligned positions. It also often occurs that the tiles are not fitted together properly when laid with the result that an abnormal space is left between the same through which earth may find its way and eventually plug the tiles.

65

By the present invention we provide a device which eliminates misalignment of the tiles and prevents the earth from finding a free passage through the joints between the same. As illustrative of the present invention we show in the accompanying drawing a pair of tiles 15 and 16 in axial alignment, and having their ends in substantially abutting relationship but spaced sufficiently from each other so that the joint 17 between the same affords a passage for water from the exterior to the interior of the tiles. Surrounding the ends of the tiles 15 and 16 over the joint 17 in overlapping relationship in respect thereto is a strip of material 18 incorporating the present invention.

75

In the form shown in Figs. 1 to 5, inclusive, and in Fig. 8 the band 18 is formed of a type of material similar to or the same as conventional roofing material having one surface thereof covered with crushed stone,

80

85

90

95

100

crushed slate, gravel or like material 19 as best shown in Fig. 3. In the form shown in Figs. 1 to 4 inclusive, the band 18 is of a length substantially equal to the circumference of the tiles 15 and 16 and is placed about 5 the same over the band 17 as indicated in Fig. 1 with the surface provided with the material 19 in contact with the surface of the tiles as indicated in Fig. 2, the ends of the 10 band 18 extending in substantially contacting relationship and being secured together by a clip 20. As indicated in Figs. 1 and 4, the clip 20 is formed from sheet metal and bent into a U-shape, the ends of which are 15 pointed, the bottom of the U contacting against the surface of the tiles and the pointed ends projecting up through the free ends of the band 18 as indicated by dotted lines in Fig. 4, and that portion of the ends which 20 projects through the band 18 being bent over as indicated in full lines in Figs. 1 and 4, thereby securing the ends of the band 18 against separation. The material of the band 18 as shown in the above discussed figures is 25 preferably of any conventional roofing material provided with the material 19 on one side thereof, such roofing material as a general rule being made of a coarse grade of paper treated with tar, asphalt or the like, 30 although it will be readily understood that a strip of fabric or metal similarly treated and provided with the material 19 on one surface thereof will equally serve the purposes of the present invention and is included there- 35 in. Such material as described when properly treated with tar, asphalt or similar material will withstand the deteriorating action of the damp earth to which they are subjected in the use as herein described for a period 40 of from 15 to 30 years, depending upon the character of the soil and the amount of moisture in the same.

In placing the band 18 about the tiles 15 and 16 in overlapping relationship to the 45 joint 15 it will be apparent that the band 18 in effect forms a sleeve in which the adjacent ends of the tiles 15 and 16 are socketed, thus holding the tiles in alignment, and at the same time the material 19 disposed between the 50 band 18 and the adjacent surfaces of the tiles provides a multitude of passageways through which the water in the earth surrounding the tiles may find its way to the joint 17 and thence into the interior of the tiles and be 55 carried away.

In practice, the method employed in using the bands of the present invention is as follows: When the trench is dug, the tiles are laid end to end within the same, care prefer- 60 ably being taken to have the same positioned on a substantially firm bed of earth and in axial alignment with each other. A band 18 is slipped over the joint 17 between each pair of tiles, the clip 20 is placed between the 65 free ends of the band 18 and the ends of the

band 18 are then forced down over the ends of the clip, thus forcing the ends of the clip through the ends of the band, and the clip ends are then bent over, thus holding the band 18 securely in place after which the trench may be back-filled. It will be readily apparent that where the bed of earth beneath the tiles before back-filling is imperfect and such that in the conventional manner of laying tiles would give upon back-filling and allow the tiles to become misaligned, the device of the present invention will hold such ends in alignment in spite of such fault of the bed below the tiles, and prevent such misalignment and consequent entrance of earth into 70 the tiles.

Although we have shown in Figs. 1, 2 and 3 a particular method of securing ends of the band 18 in position over the joint 17, it will be understood that the method shown is merely illustrative of any suitable manner of securing such ends together, and other means for holding the band 18 in place such as illustrated in Figs. 5 and 8, or any other means may be employed. In Fig. 5 a simple method of securing the ends of the band together is shown. In that figure the band 18 is made slightly longer than the circumference of the tiles, the ends being overlapped when the band is in place and a split rivet such as 90 21 is driven through the overlapping portions of the band, the ends of the rivets spreading when driven against the tiles and holding the band securely in place. In Fig. 8 the band is positioned over the joint 17 and one or 95 more wires 22 is extended around the same and twisted together thus holding the band 18 securely in position. Other similar means are readily suggested and may be employed when desired.

In Figs. 6 and 7 a modified form of band is shown. In this modification the band 23 is formed of the same material as the band 18 but instead of being provided with the material 19 on one surface thereof, that surface is provided with a series of grooves or corrugations 24 which may be molded, rolled or otherwise formed in the one surface of the material to thereby provide water passages in the same manner that the material 19 forms water passages for the band 18. The band 23 may be secured in place in the same manner as described in connection with the band 18, but we have shown a modified manner of securing the same in place comprising one or more wires 25 which are preferably molded or otherwise formed within the band 18 longitudinally of the same, the wires 25 projecting past the adjacent ends of the band and being twisted together as indicated in Fig. 7 to 110 hold the band in position.

Formal changes may be made in the specific embodiment of the invention described without departing from the spirit or substance of the broad invention, the scope of 115 120 125 130

which is commensurate with the appended claims.

What we claim is:

1. A device for securing adjacent ends of drain tiles in alignment comprising a flexible band split transversely of its length and adapted to be bent around the said ends, the surface of said band adapted to contact with said tiles, being provided with means artificially applied thereto permitting the drainage of water between said band and said tiles.

2. A device for holding adjacent ends of drain tiles in alignment comprising a flexible band split transversely of its length and adapted to be bent about said tiles in overlapping relationship with respect to the joint between the same, said band being provided with a surface coating in contact with said tiles permitting the drainage of water between said band and said tiles.

3. A device for holding adjacent ends of drain tiles in alignment comprising a strip of material one surface of which is provided with a plurality of spaced projections adapted for substantially point contact with the surface of said tiles upon being bent therearound.

4. A device for holding adjacent ends of drain tiles in alignment comprising a band to the inner surface of which a plurality of small particles of material are secured by adherence therewith, said particles adapted to hold said band out of contact with said tiles.

5. A device for holding adjacent ends of drain tiles in alignment comprising a bituminous treated band adapted to extend around a pair of tiles in overlapping relationship with respect to the joint between the same, the surface of said band next to said tiles being provided with a plurality of spaced upstanding projecting particles thereon.

6. A device for holding adjacent ends of drain tiles in matching relationship comprising a band adapted to extend around said tiles in overlapping relationship with respect to the joint between the same, said band comprising a bituminous treated strip of material one surface of which is provided with crushed rock adhering thereto.

7. A device for holding adjacent ends of a pair of drain tiles in matching relationship comprising a band of bituminous treated flexible material adapted to overlap the joint between the said tiles and provided with spaced means on the inner surface thereof adapted to contact with said tiles permitting the drainage of water between said band and said tiles to said joint.

8. A device for holding the adjacent ends of drain tiles in alignment comprising a strip of readily bendable material adapted to be bent around the adjacent ends of said tiles in overlapping relationship with respect to the joint between them, said strip having a

pebbled surface adapted to contact with the surface of said tiles.

9. A device for holding the adjacent ends of drain tiles in alignment comprising a flexible strip of material having a pebbled surface, said strip adapted to be bent around the adjacent ends of adjacent tiles in overlapping relation with respect to the joint between them and with said pebbled surface in contact with said tiles whereby to permit the drainage of water between said tiles and band to said joint.
